UNITED STATES PATENT OFFICE

138,512

DESIGN FOR A STAR CORSAGE OR SIMILAR ARTICLE

Robert Dunie, Chicago, Ill.

Application April 15, 1944, Serial No. 113,267

Term of patent 3½ years

(Cl. D29—1)

To all whom it may concern:

Be it known that I, Robert Dunie, a citizen of the United States of America, and a resident of Chicago, in the county of Cook and State of Illinois, have invented a new, original, and ornamental Design for a Star Corsage or Similar Article, of which the following is a specification, reference being had to the accompanying drawing, forming part hereof.

In the drawing:

Fig. 1 is a front elevational view of a star cor-

sage or similar article showing my new design,

Fig. 2 is partly a side elevational and partly a vertical sectional view thereof, taken on the line 2—2 of Fig. 1.

The drawing is lined to show contrasting colors.

I claim:

The ornamental design for a star corsage or similar article, substantially as shown.

ROBERT DUNIE.
